UNITED STATES PATENT OFFICE.

CHARLES W. SEARS, OF OMAHA, NEBRASKA.

ROTARY INTERNAL-COMBUSTION ENGINE.

1,222,475.

Specification of Letters Patent. Patented Apr. 10, 1917.

Application filed April 19, 1916. Serial No. 92,184.

To all whom it may concern:

Be it known that I, CHARLES W. SEARS, a citizen of the United States, residing at Omaha, in the county of Douglas and State of Nebraska, have invented new and useful Improvements in Rotary Internal-Combustion Engines, of which the following is a specification.

My present invention relates to improvements in internal combustion engines, and more especially to those of the rotary type employing a rotary member or rotor and a co-operating or stationary member or stator, reaction resulting from the explosions of charges of combustible gas causing relative rotation between the rotor and stator.

The primary objects of the invention are to provide an internal combustion engine of this type which will be compact in proportion to the power it is capable of developing, one which will produce a substantially constant and uniform torque between the rotor and stator, and one which will operate with relatively high efficiency owing to the relatively high compression to which the explosive charges are subjected at the moment of ignition.

In the preferred embodiment of the invention, the engine comprises a rotor, preferably in the general form of a wheel, and a stator in the general form of an annular drum or casing surrounding the wheel, the periphery of the wheel having a series of circumferentially arranged combustion chambers and co-operating piston blades and carrying a corresponding series of pistons and cylinders operative to draw in and compress charges of explosive gas and to discharge the compressed charges successively into the peripheral chambers of the rotor or wheel, the stator or drum having an intake for supplying the explosive gas to the compressing cylinders successively as the latter reach a predetermined position in their rotation about the axis of the wheel, and the stator or drum having a combustion chamber and ignition means, therefor and into which combustion chamber the compressed charges of explosive gas are successively introduced, to be exploded therein by the ignition means. The impulses of the explosive explosions in the combustion chamber or drum act on the piston

blades, thereby rotating the rotor or wheel, means being provided whereby rotation of the wheel serves to perform the cycle of converting the force of the explosions into a force operating to drive the wheel, exhausting the products of the explosions from the chambers of the wheel and drum, drawing in a fresh charge, and compressing such charge preparatory to ignition thereof.

Subsidiary objects of the invention are to provide charge-compressing devices which introduce the compressed charges of explosive gas into the respective combustion chambers of the wheel and are then cut off from communication with such combustion chambers prior to ignition; to provide piston blades which operate to confine the compressed explosive charges in the respective chambers in the wheel until these charges successively reach the combustion chamber of the drum or casing; to provide piston blades which are adapted to move outwardly beyond the periphery of the wheel and into the combustion chamber of the drum to receive the impulses of the respective explosions, these piston blades preferably operating to expel products of combustion remaining in the chambers of the wheel; to provide means for blowing the products of combustion from the zone of the ignition means and from the combustion chambers of the wheel and drum, this action assisting in cooling the engine and the parts thereof which are subjected to relatively high temperature; to provide relatively simple and efficient means for actuating the charge-compressing pistons and cylinders in correct relation to the rotation of the wheel; to provide means for maintaining a correct gas-tight fit of the rotor within the stator, compensating automatically for wear and contraction and expansion due to temperature variations; and to provide simple and efficient lubricating means.

To these and other ends, the invention consists in certain improvements, and combinations and arrangements of parts, all as will be hereinafter more fully described, the novel features being pointed out particularly in the claims at the end of the specification.

In the accompanying drawings:—
Figure 1 represents a central vertical sec-

tion of an internal combustion engine constructed in accordance with the present invention, the section being taken in the medial plane of the rotor or wheel.

5 Fig. 2 represents a section taken diametrically of the engine and on the line 2—2 of Fig. 1.

10 Fig. 3 represents a section of the right-hand portion of the stator or drum in the plane of the intake port for the explosive gas.

15 Fig. 4 is a detail perspective view of one of the piston blades, and

20 Fig. 5 is a face view of one of the members which serves to actuate the charge-compressing devices, this member being shown coupled to the shaft.

25 Similar parts are designated by the same reference characters in the several views.

30 The preferred embodiment of the invention is shown in the accompanying drawings and will be hereinafter described in detail. It is to be understood, however, that the invention is not restricted to the particular construction shown, as modifications and changes may be made therein and equivalent constructions are contemplated within the scope of the claims. It is also to be understood that certain features of the invention are applicable generally to internal combustion engines of different types, and hence such features are not limited to an engine of the particular type herein shown.

35 In the present instance, 1 designates the rotor, which is generally in the form of a wheel of appropriate diameter and axial length, its dimensions being determined by the capacity of the engine and the number of combustion chambers, piston blades and associated charge-compressing devices. Preferably, the rotor or wheel is of generally cylindrical form, it being shown as comprising a rim which contains the operative elements and spokes 2 which connect the rim to the hub 3, the latter being keyed or otherwise fixed to a shaft 4. The spaces between the spokes and at the inner circumference of the rim of the wheel provide oil chambers, and the distribution of oil from these chambers 40 for lubricating purposes will be hereinafter described. The stator 5 comprises generally an annular drum or casing, it being of a greater axial length than the rotor or wheel, as will be understood from Fig. 2, and it is 45 bored internally to form a revolving gas-tight fit with the periphery of the rotor or wheel. In order to take up wear on the periphery of the rotor or wheel and the cooperating inner wall of the stator or drum, 50 and furthermore to compensate for expansion and contraction of the rotor and stator, due to temperature changes, the drum is split, it being shown as split at the top in the present instance, a radially extending slot 6 being formed to permit the diameter

of the stator or drum to change as conditions may require, and a gas-tight joint is provided for this slot, a packing strip 7 being shown for this purpose in the present instance the edges of which are recessed in the 70 meeting or adjacent ends of the drum so that the packing strip intersects the slot. Means is provided for holding the split ends of the drum in proper relation. Preferably, and as shown, means is provided which acts to 75 yieldingly draw the split portions of the drum together with a tendency to close the slot 6. For example, bolts 8 may be provided which pass through apertured lugs 9 on the exterior of the drum at opposite sides of 80 the slot 6, and springs 10 may be interposed between these lugs and the nuts or heads 11 of the bolts.

85 Piston blades of a suitable number are pivotally mounted on the rotor or wheel, these piston blades being capable of occupying a position flush with the periphery of the wheel, or substantially so, and occupying a position where they project outwardly beyond the periphery of the wheel. The 90 number of piston blades employed may be varied as desired, this usually depending upon the power of the engine and the number of impulses to be given the rotor for each revolution thereof. It is preferable, 95 however, that these piston blades should be equidistantly spaced circumferentially of the rotor or wheel, and that they should be sufficiently close in a circumferential direction to enable the impulses to be imparted to the 100 rotor or wheel at such close intervals as to produce a constant or a substantially constant torque on the shaft. Each piston blade is designated 12, it having a pivot or knuckle 13 seated so as to rock in a socket 14 in 105 the wheel. Each piston blade preferably has a segmental or sector-like portion 15 which is adjacent to the pivot or knuckle 13 and from which the blade portion of the piston projects in an approximately radial direction. The periphery of the wheel is provided with a suitable number of circumferentially spaced recesses to accommodate the piston blades. Each recess in the wheel comprises a segmental or sector-like portion 16 to accommodate the correspondingly shaped portion 15 of the piston blade and a chamber 17 which forms the combustion chamber, and a space beyond it to accommodate the outer or free end of the piston blade. The combustion chamber is preferably of an approximately cylindrical form, it having a truncated bottom 18 and a port 19 extending therethrough for the admission of the compressed explosive charge from the respective compressing device, as will hereinafter appear. Toward the outer end of the cylindrical combustion chamber are provided seats 20 and 21, and these seats are adapted to be engaged by the inner wall 22 of the pis- 110

115

120

125

130

ton blade when the latter occupies its innermost position within the wheel, the piston blade then closing the cylindrical combustion chamber tightly and serving, as will 5 hereinafter appear, to confine a compressed explosive charge therein. The sides of the piston blade have a close or pressure-tight fit with the sides of the recess in the wheel to prevent leakage of fluid past the piston blade. It is preferable to provide means for 10 limiting the outward movement of the piston blade. As shown, the segmental wall 23 of the recess in the wheel is provided with a notch 24, and the segmental or sector-like portion of the piston blade is provided with a strip or projection 25 which is adapted 15 to extend into the notch 24 and to abut against the outer end of this notch, thereby preventing further outward swing of the piston blade. The limiting stop 25 may be held in position and adjusted as may be required by one or more screws 26 extending inwardly from the outer side of the piston blade and abutting against the limiting stop 25. The outer side of each piston blade has 20 a portion 27 toward its free end which is concentric with the axis of the wheel and is adapted to be flush with the periphery of the wheel when the piston blade occupies its innermost position, and the piston blade also has a plane portion 28 which inclines inwardly from the concentric portion 27 to or toward the pivot or knuckle 13, this plane portion of the piston blade, when the 25 latter occupies its innermost position, forming a pocket 29 in the periphery of the wheel. Means is provided for taking in a charge 30 of explosive gas, compressing the same, and introducing the compressed charge into the combustion chamber in the wheel for each 35 piston blade. These compressing devices are spaced circumferentially of the wheel and they preferably correspond in number to the number of piston blades employed. Each 40 compressing device comprises, in the present instance, a cylinder 30 mounted to reciprocate with a fluid-tight fit in a bore 31 formed in the rim of the wheel and extending axially of the wheel, and a piston 32 which is 45 mounted to reciprocate with a fluid-tight fit within the cylinder 30. The cylinder 30 is provided with a head 33 and a port 34 in one side thereof immediately adjacent to the head. The rim of the wheel is provided 50 with a radial intake port 35 for each piston blade. This intake port is, as shown in Fig. 2, located in the rim of the wheel at one side of the piston blade and it registers with the port 34 of the cylinder when the respective 55 cylinder reaches a point in its rotation which brings it opposite to or in register with the gas intake port 36 in the drum. The intake port 36 in the drum is in communication with a carbureter 37 which may be of the 60 usual type employed on internal combustion

engines for supplying hydrocarbon or other gaseous fuel. When the rotation of the wheel brings the ports 34, 35 and 36 into register, the piston 32 and the cylinder head 33 are separated to their maximum distance. 70 The separating movement of the piston and cylinder head produces a vacuum in the cylinder, and when the ports just stated come into register, a charge of explosive gas is forced by atmospheric pressure through the carbureter and into the cylinder. As the rotation of the wheel or rotor continues, the port 35 in the rotor or wheel is carried in a circumferential direction out of register with the intake port 36 in the drum, and the port 34 in the cylinder is moved in an axial direction out of register with the intake port 35 in the rim of the rotor or wheel. The charge of gas introduced into the cylinder 30 is then compressed by movement of the piston 32 and the cylinder head 33 toward one another, this compression of the charge continuing, owing to the confinement of the charge, until the port 34 comes in register with the port 19, which latter port leads into 80 the respective combustion chamber in the periphery of the rotor or wheel. When this occurs, the compressed charge is transferred from the cylinder to the combustion chamber in the periphery of the rotor or wheel and the receding movement of the cylinder 30 which follows immediately after the transfer of the charge carries the port 34 of the cylinder out of register with the port 19 and the compressed explosive charge is then confined in the combustion chamber in the periphery of the wheel by the inner wall 22 of the corresponding piston blade, the latter at this time engaging the seats 20 and 21 which 85 seal the combustion chamber. Suitable means, such as a rib 30^a on the cylinder 30 and a co-operating groove 30^b in the bore 31, serves to prevent rotation of the cylinder, and hence the port 34 in the cylinder will be maintained in line with the co-operating 90 ports 19 and 35. 100

The present invention provides relatively simple means for effecting reciprocation of the several cylinders and pistons 30 and 32 respectively, to draw in the explosive charges, compress such charges, and transfer the compressed charges to the respective combustion chambers in the periphery of the wheel in proper relation to the rotation of the wheel. As shown, the actuating means for the compressing cylinders and pistons 105 comprises a pair of disks or heads 38 and 39 which are preferably circular in form and have their peripheries rotatably engaged in grooves 40 and 41 formed in rings or annular members 42 and 43 respectively. The rings or annular members 42 and 43 are preferably formed separately from the drum and are fitted into the ends thereof at opposite 110 sides of the rim of the rotor or wheel. The 115

120

125

130

grooves 40 and 41 of these rings or annular members lie in planes which are inclined in reverse directions relatively to the axis of the shaft 4, the axis of inclination of these planes relatively to the shaft being designated by the line $x-y$ in Fig. 1 for a purpose that will hereinafter appear. The grooved rings or members 42 and 43 are held non-rotatably within the drum while the heads or disks 38 and 39 rotate in unison with the rotor or wheel but they maintain the axis of inclination relatively to the drum as designated by the line $x-y$ in Fig. 1. The means shown in the present instance for causing rotation of the disks or heads 38 and 39 in unison with the rotor or wheel comprises a pair of driving hubs 44 and 45 which are keyed or otherwise fixed to turn with the shaft 4 and have a suitable number 20 of ribs 46 and 47, the ribs of each hub lying within the circumference of a sphere and engaging in grooves 48 in the respective disk 38 or 39 and thereby forming a driving connection between the shaft and the respective 25 disk, although permitting each disk to follow the inclined groove 40 or 41 as the shaft revolves. Rotation of the shaft causes the two disks to alter their direction of inclination relatively to the shaft, although their 30 inclination relatively to the drum is maintained. The different cylinders 30 are operatively connected to the disk 38 while the pistons 32 are operatively connected to the disk 39. In the present instance, a rod 49 35 connects each cylinder to the disk 38, the rod having a universal joint connection with the disk. As shown, it has a spherical head 50 which is engaged in a spherical socket 51 formed between a pair of tapered bearing 40 members 52, the latter fitting into a tapered seat 53 in the disk, and screws or bolts 54 serve to draw the tapered bearing members into the seat and to hold them therein in proper adjusted relation to the spherical 45 head 50. Each piston 32 has a rod 55 which connects it to the disk 39, each rod having a universal joint connection with the disk 39 which may be of the same construction as that just described in connection with the 50 rods 49. Owing to the reverse inclination of the disks 38 and 39 on the line $x-y$ relatively to the drum, the cylinders 30 and the pistons 32 are caused to approach and recede relatively to one another as the wheel 55 revolves, performing the cycle of operations as hereinbefore described.

The ends of the drum are closed by heads 56 and 57, and these heads are preferably utilized to support bearings for the shaft 4. 60 As shown, the heads are clamped against the ends of the drum by bolts or other suitable devices 58, and suitable means is provided for effecting fluid-tight fits between the heads and the ends of the housing. As 65 shown, grooves 59 having oppositely sloping walls are formed on the inner faces of the heads to receive the correspondingly shaped ends of the drum, and gaskets 60 may be fitted into these grooves and clamped therein by tightening of the bolts 58. Bearings 61 and 62 are supported in the heads and coöperate with the shaft 4. To provide for lubrication of these bearings, lubricating passages 63 and 64 are extended downwardly from lubricant-collecting pockets 65 70 and 66 formed at the tops of the bearings to receive oil lifted by the rotor or the respective disks 38 and 39, the lubricating passages 63 and 64 serving to conduct this oil to the interior of the bearing. Lubrication of the 75 piston blades and the cylinders 30 and pistons 32 is also provided for. As shown, a lubricant-conducting passage 67 leads from the space between each pair of adjacent spokes 2 and from the inner circumference 80 of the rim of the wheel into the segmental or sector-shaped portion 16 of the recess which contains the correspondingly shaped portion of each piston blade, and another lubricant-conducting passage 68 leads from the inner circumference of the rim of the wheel to the bore 31 in which the cylinder 30 reciprocates. Oil is supplied to the lower half of the drum and this oil is lifted by the wheel as the latter revolves, some of the oil 85 reaching the inner circumference of the rim of the wheel and then flowing through the oil-conducting passages 67 and 68 to the operative parts of the wheel. The oil flowing through the passages 67 and 68 eventually reaches the periphery of the wheel, owing to centrifugal action, and supplements the oil in the lower half of the drum in maintaining an oil film between the periphery of the wheel and the piston blades and the interior bore of the drum.

The interior bore of the drum is provided with an ignition chamber 69 which is located slightly beyond the axis $x-y$, and this ignition chamber contains suitable ignition means, it being preferable to employ a pair of spark plugs 70 adapted to be connected to any suitable ignition system capable of producing sparking at the plugs at appropriate intervals or in timed relation to the passage of the piston blades relatively to the ignition chamber. The interior bore of the drum is provided with a gas expansion or combustion chamber, it being shown in the form of a groove 71 into which the free ends of the piston blades are adapted to fit so as to permit movement of these piston blades but prevent leakage of gas past the piston blades. An incline 72 leads from the ignition chamber 69 to the groove 71 forming the combustion chamber, and an exhaust port 73 is provided in the drum at the end of the combustion chamber. The limiting stops 25 of the piston blades are so adjusted that they will just permit the free

ends of the piston blades to reach the bottom of the groove 71, thereby reducing the pressure and consequently the friction and wear of these piston blades to a minimum. Beyond the exhaust port 73 the interior circumference of the drum is formed with an incline 74 which extends inwardly to substantially the periphery of the wheel, and beyond this incline 74 and in advance of the intake port 36 the interior of the drum is formed with a groove 75 whereby the piston blades will be caused to move into the recesses of the wheel by the incline 74 after the piston blades pass the exhaust port, and the piston blades will be permitted to again swing outwardly from the recesses of the wheel before reaching the intake port. The lower half of the drum which extends between the intake port 36 and the ignition chamber 69 is preferably ungrooved so that the piston blades will be held within their recesses in the wheel during the corresponding half of the revolution of the wheel.

In order to insure complete clearing of the combustion chambers of the products of combustion and to also assist in cooling the engine, a port 76 may be provided immediately in advance of the ignition chamber 69, this port being connected by a pipe 77 to a suitable source of compressed air. A similar port 78 may be provided in the drum and leading into the lower end of the groove 75, this port being adapted to supply compressed air from a suitable source through a pipe 79 to the groove 75. In the operation of the engine, the inner end of the port 76 will be uncovered by the pocket 29 at the outer side of each piston blade as the latter passes the port 76, communication being thereby established between the port 76 and the ignition chamber 69, and in consequence, a blast of cool air will act on the ignition points or electrodes of the spark plugs to clear them of foul or burned gases and to cool them. The air so introduced will flow through the combustion chamber formed by the groove 71 and will be vented through the exhaust port 73. The cool air introduced into the groove 75 by the port 78 will carry any products of combustion remaining in the groove 75 or in the combustion chambers of the wheel out of the vent 80. If desired, an exhaust fan or other suction device may be connected to the vent 80 to facilitate this action. In both instances, the cool compressed air introduced into the drum will cool the interior thereof and the pistons and other operative parts. Of course, a water or other cooling system may be provided for the housing and the wheel also, if desired. The drum is provided at the bottom with a base 81 whereby it may be clamped or bolted to an appropriate support.

The cycle of operations may be briefly de-

scribed as follows: Assuming that the intake port 36 is connected to a carburetor or other device for supplying gaseous fuel, and that the spark plugs are connected to a suitable ignition system, the engine may be started by rotating the shaft in a clockwise direction. As each piston blade passes the intake port, it is moved into its recess in the rim of the wheel, and the cylinder 30 and piston 32 comprising the charge-compressing means for this piston blade, after having received a charge of explosive gas, begin to approach one another. As this piston blade moves from the intake port in a clockwise direction, the compressing of the charge proceeds, owing to the approaching movements of the cylinder head 33 and the coöperating piston 32. When this cylinder 30 reaches the line $x-y$, the piston 32 and cylinder head 33 will be at the limits of their approaching movements, the charge between the piston and cylinder head will be compressed to the highest degree, and the port 34 in the cylinder will be in register with the port 19 leading to the corresponding combustion chamber in the rim of the wheel. The compressed charge will, in consequence, be transferred from the cylinder into the corresponding combustion chamber in the wheel and the charge will be retained in this combustion chamber by the engagement of the wall 22 of the piston blade with the seats 20 and 21 which seal the combustion chamber. At substantially this point in the rotation of the wheel, the pocket 29 will uncover the inner end of the port 76 and permit a blast of air past the electrodes of the ignition plugs for the purpose hereinbefore described. Further rotation of the wheel permits receding of the piston 32 and the cylinder head 33, carrying the port 34 out of register with the port 19 leading to the combustion chamber in the rim of the wheel, thereby interrupting communication between these parts. At this point in the rotation of the wheel, the free end of the piston blade reaches the incline 72 leading outwardly and into the groove 71 which forms the combustion chamber in the drum. As the piston blade moves outwardly, it unseals or uncovers the combustion chamber in the rim of the wheel, permitting the compressed explosive charge previously confined therein to escape into the ignition chamber 69, the spark passing at this moment and thereby igniting the charge. As the wheel continues to revolve, the piston blade swings outwardly beyond the periphery of the wheel, and the exploded gas produces an impulse upon the piston blade tending to drive the wheel in a clockwise direction. As the piston blade traverses the groove 71 in the drum, the exploded charge expands and the products of combustion of the charge are exhausted through the port 73 when the piston blade

passes that port. As the piston blade reaches the incline 74, it is returned to a position within the recess of the wheel, thereby expelling products of combustion 5 contained beneath it. After the piston blade has passed the incline 74, it again swings outwardly by centrifugal force into the groove 75, thereby uncovering the combustion chamber in the rim of the wheel and 10 permitting any products of combustion remaining in the combustion chamber to escape into the groove 75 and to pass out of the drum through the vent 80. Clearing of the combustion chamber of burned gases is 15 facilitated by the blast of air entering the drum through the port 78, as previously described. While the piston blade is moving from the ignition chamber in a clockwise direction to the intake port, the piston 32 and cylinder head 33 are receding. At substantially the moment the corresponding cylinder 20 30 reaches a point opposite to the intake port, the port 34 in this cylinder is in register with the intake port 35 in the rim of the wheel, and the intake port 35 in the rim of 25 the wheel comes in register with the intake port 36 in the drum. The vacuum produced in the cylinder 30 by reason of the receding motion of the piston 32 and cylinder head 33 then permits another charge of explosive 30 gas to enter the cylinder from the carburetor. The cycle of operations just described is repeated at each revolution of the wheel or rotor, and this cycle of operations is performed by each piston blade and its charge-compressing means.

By employing a circumferential series of piston blades and associated compressing means, the successive impulses imparted to 40 the rotor or wheel produce a torque on the shaft which is constant, or substantially so, and the power may be developed at a relatively low speed of the shaft. Efficiency of the engine is increased in comparison with 45 engines of the ordinary reciprocating type by causing the impulses to act on the rotor or wheel in substantially the line of movement of the periphery thereof, conversion of reciprocating motion into rotary motion 50 with its consequent vibration and loss of power being avoided. By cutting off communication between the compressing cylinder and the corresponding combustion chamber immediately prior to the explosion in 55 such combustion chamber, the efficiency of the engine is increased, in that it confines the exploded gases to the combustion chamber, thus producing a higher explosion pressure, and the force of the explosion is 60 not sustained by the compressing cylinder and piston and, in consequence, these parts may be made of relatively light construction, straining thereof is avoided, and undue wear of these parts is avoided. Furthermore, no 65 waste products of combustion remain in the

compressing cylinders, and hence each cylinder will, at each stroke, take in a full charge of explosive gas.

I claim as my invention:—

1. An internal combustion engine comprising a rotor having a combustion chamber therein, a stator, means carried by the rotor for compressing an explosive charge, means for introducing a compressed charge from said compressing means into said combustion chamber and operative subsequently to interrupt communication between the charge compressing means and said chamber, and means for causing said charge when exploded to act in a peripheral direction upon the rotor. 70

2. An internal combustion engine comprising a rotor, a stator, a combustion chamber in the rotor, means for igniting an explosive charge in said chamber, means for confining a compressed explosive charge in said chamber prior to ignition thereof, and charge compressing means for introducing a compressed explosive charge into the combustion chamber and having means for cutting it off from communication with said chamber prior to ignition of such charge. 85

3. An internal combustion engine comprising a rotor, a stator, a combustion chamber in the rotor, means for igniting an explosive charge in said chamber, means for confining a compressed charge in said chamber and operative to cause its release and ignition, and charge compressing means for supplying a compressed explosive charge for said chamber and adapted to be put out of communication with said chamber prior to the explosion of such charge in the combustion chamber. 95

4. An internal combustion engine comprising a rotor, a stator, a chamber being provided in the periphery of the rotor, charge compressing means carried by the rotor for supplying a compressed explosive charge to said chamber, means for confining such charge in said chamber, and means for igniting the charge in said chamber after communication between the latter and the compressed charge-supplying means has been interrupted. 105

5. An internal combustion engine comprising a drum having a combustion chamber, a wheel rotatably fitting in said drum and having a chamber in its periphery, means for compressing and supplying an explosive charge to the chamber in the wheel, and a member movable into a position to cover and thereby confine such charge in the latter chamber and subsequently movable into a position to cause such charge to enter the combustion chamber of the drum. 120

6. An internal combustion engine comprising a drum having a combustion chamber, a wheel rotatably fitting in said drum 125

- and having a chamber in its periphery, means for compressing and supplying an explosive charge to the chamber in the wheel, and a piston blade carried by the wheel operative to confine such charge in the latter chamber and subsequently movable into a position to cause such charge to enter the combustion chamber of the drum. 5
7. An internal combustion engine comprising a drum having a combustion chamber, a wheel rotatably fitting in said drum and having a chamber in its periphery, means carried by the wheel for compressing and supplying an explosive charge to the chamber in the wheel, and a piston blade carried by the wheel operative to confine such charge in the latter chamber and subsequently movable into a position to cause such charge to enter the combustion chamber 10 of the drum, the piston blade being arranged to operate in the combustion chamber of the drum and to transmit an impulse resulting from the explosion of such charge to the wheel. 15
- 20 8. An internal combustion engine comprising a drum having a combustion chamber, a wheel rotatably fitting in said drum and having a chamber in its periphery, a charge-compressing cylinder carried by the wheel and operative to supply a compressed explosive charge to the chamber in the wheel, and means operative subsequently to admit a portion of such charge to the combustion chamber in the drum. 25
- 30 9. An internal combustion engine comprising a drum having a combustion chamber, a wheel rotatably fitting in said drum and having a chamber in its periphery, means for supplying a compressed explosive charge to the chamber in the wheel, means for confining such charge in the latter chamber and subsequently causing such charge to enter the combustion chamber of the drum, and means for interrupting communication 35 between the charge-supplying means and the chamber in the wheel prior to entry of such charge into the combustion chamber in the drum. 40
- 45 10. An internal combustion engine comprising a drum having a combustion chamber, a wheel rotatably fitting in said drum and having a chamber in its periphery, a charge-compressing cylinder carried by the wheel and having means for establishing and interrupting communication between it and said chamber in the wheel, means operative by rotation of the wheel to cause compression of an explosive charge in said cylinder and transfer of such charge to the chamber in the wheel, and means operative to cause flow of such charge from the chamber in the wheel into the chamber in the drum. 50
- 55 11. An internal combustion engine comprising a drum having a combustion chamber, a wheel rotatably fitting in said drum and having a chamber in its periphery, a charge-compressing cylinder carried by the wheel and having means for establishing and interrupting communication between it and said chamber in the wheel, means operative by rotation of the wheel to cause compression of an explosive charge in said cylinder and transfer of such charge to the chamber in the wheel, and means operative to cause flow of such charge from the chamber in the wheel into the chamber in the drum. 60
- 65 12. An internal combustion engine comprising a drum having a combustion chamber, a wheel rotatably fitting in said drum and having a chamber in its periphery, a charge-compressing cylinder carried by the wheel and having a port adapted to establish and to interrupt communication between it and the chamber in the wheel, means operative by rotation of the wheel to cause compression of an explosive charge in the cylinder to subsequently establish communication between said port in the cylinder and the chamber in the wheel and to thereafter interrupt communication between said cylinder port and the latter chamber, and means controlling the flow of the charge from the chamber in the wheel into the chamber in the drum. 70
- 75 13. An internal combustion engine comprising a rotor having a piston member pocketed in the periphery and movable into a position projecting beyond said periphery, a stator having a combustion chamber adapted to receive said piston member when projected, and means for supplying a compressed explosive charge to said combustion chamber to be confined therein by said piston member and to be exploded and to act therein against said piston member. 80
- 85 14. An internal combustion engine comprising a rotor having a piston member pocketed in its periphery and movable into a position projecting beyond said periphery, a stator having a combustion chamber adapted to receive said piston member when projected, and charge compressing means carried by the rotor for supplying a compressed explosive charge to said combustion chamber in the rotor to be confined therein under control of said piston member. 90
- 95 15. An internal combustion engine comprising a rotor having a piston member pocketed in its periphery and movable into a position projecting beyond said periphery, a chamber being formed in the rotor beneath said piston member, a stator having a combustion chamber arranged to receive said piston member when the latter is projected, and means for compressing and supplying an explosive charge to the chamber beneath 100
- 110 120 125 130

the piston member to be confined therein by said piston member.

16. An internal combustion engine comprising a drum having an explosive gas intake at a point in its periphery, and an approximately diametrically opposite combustion chamber, a wheel rotatably fitted into said drum and having a combustion chamber therein, means carried by the wheel for drawing in an explosive charge from said intake and operative to compress such charge, means for introducing the compressed charge into the combustion chamber of the drum to be ignited therein, and a piston member movable to cover and uncover said combustion chamber of the wheel.

17. An internal combustion engine comprising a wheel having a recess in its periphery forming a combustion chamber at the bottom thereof, a piston member movable into and out of said recess, means for supplying an explosive charge to said chamber to be held under compression therein by said piston member, and a drum into which said wheel is revolvably fitted and having a combustion chamber to receive said piston member and controlling the movement thereof relatively to its recess in the wheel.

18. An internal combustion engine comprising a wheel having a recess in its periphery forming a combustion chamber at the bottom thereof, a piston member movable into and out of said recess, means for supplying an explosive charge to said chamber to be confined therein under compression by said piston member, and a drum into which said wheel is revolvably fitted and having a combustion chamber to receive said piston member, an incline to return the piston member to its recess after traversing said combustion chamber, and a chamber to cause subsequent movement of the piston member out of its recess.

19. An internal combustion engine comprising a wheel having a recess in its periphery forming a combustion chamber at the bottom thereof, a piston member movable into and out of said recess, means for supplying an explosive charge to said chamber, a drum into which said wheel is revolvably fitted and having a combustion chamber to receive said piston member, an incline to return the piston member to its recess after traversing said combustion chamber and means for producing a blast or fluid through said latter chamber while the piston member is out of its recess.

20. An internal combustion engine comprising a drum containing an ignition chamber, a wheel rotatably fitted in said drum, means for supplying an explosive charge to said ignition chamber to drive said wheel, and means for producing a flow of a clearing fluid into said ignition chamber prior to

the introduction of an explosive charge 65 therein.

21. An internal combustion engine comprising a drum having a combustion chamber therein, a wheel rotatably fitted into the drum and having a recess in the periphery thereof, said recess having a notch in a wall thereof, a piston member pivotally movable out of said recess into the combustion chamber of the drum, said member having a segmented portion, a stop movably fitted in the segmental portion of the piston and operative 75 on the notched wall of said recess to limit the movement of the piston member into the combustion chamber of the drum, and means accessible from the periphery of 80 the wheel for setting and maintaining said stop in operative position in said notch.

22. In an internal combustion engine, the combination of a rotary wheel, an annular drum in which the wheel is revolvably fitted, 85 the drum being split at its periphery, and a strip overlapping and slidably engaging the split portions of the drum to retain the latter in correct fitting relation with the periphery 90 of the wheel.

23. In an internal combustion engine, the combination of a drum, a wheel revolvably fitted therein, a combustion chamber being formed between the drum and wheel, a cylinder and piston having their axes arranged 95 longitudinally of the axis of the wheel for supplying a compressed explosive charge to the combustion chamber, and means for relatively reciprocating the cylinder and piston during relative rotation between the drum 100 and wheel, comprising a member rotatable with the wheel and having means for maintaining it at a given angle of inclination relatively to the axis of the drum.

24. In an internal combustion engine, the combination of a drum, a wheel revolvably fitted therein, a combustion chamber being formed between the drum and wheel, a cylinder and piston having their axes arranged 110 longitudinally of the axis of the wheel for supplying a compressed explosive charge to the combustion chamber, and means for relatively reciprocating the cylinder and piston incident to relative rotation between the drum and wheel, comprising a pair of disks 115 at opposite ends of and rotatable with the wheel, said disks being connected respectively to the cylinder and piston, and means for maintaining the disks at reverse angles of inclination relatively to the axis of the 120 drum.

25. In an internal combustion engine embodying a drum and a wheel rotatably fitted therein and having piston blades pivotally mounted in its periphery, and charge-compressing cylinders, of lubricating means embodying a lubricant-containing chamber located substantially centrally of the wheel 125

and lubricant-conducting passages leading substantially radially from the central portion of the wheel, some of said passages leading to said piston blade and others to said 5 cylinders.

In testimony whereof I have hereunto set

my hand in presence of two subscribing witnesses.

CHARLES W. SEARS.
